UNITED STATES PATENT OFFICE.

CHARLES COLAHAN, OF CHICAGO, ILLINOIS.

GRAIN-BINDER.

SPECIFICATION forming part of Letters Patent No. 690,134, dated December 31, 1901.

Application filed October 1, 1901. Serial No. 77,187. (No model.)

To all whom it may concern:

Be it known that I, CHARLES COLAHAN, a citizen of the United States, and a resident of Chicago, county of Cook, and State of Illinois, 5 have invented certain new and useful Improvements in Grain-Binders, of which the following is a specification, reference being had to the accompanying drawings, forming a part thereof.

10 My invention has relation to grain-binders and to that part pertaining to the function of tying the knot in the band that secures the bundle, and more particularly to that form of knotter that stands in its normal position 15 with its bill pointing outwardly as the bundle is discharged and the band placed around the succeeding bundle.

My invention has for its object the economizing of band material and removing much 20 of the strain upon the twine during the compressing and binding operation and also to place the band closely around the bundle and provide slack cord for the formation of the loop, thus permitting the use of a small twine 25 and consequent saving in expense, since twine now used is often much larger and heavier than is required to hold the bundle, as the strain upon the twine in forming the knot is usually quite severe in the ordinary 30 knotters.

My present invention consists in improvements on my former patents, No. 425,565, dated April 15, 1890, and No. 476,519, dated June 7, 1892, and also patent No. 677,943, 35 dated July 9, 1901, and is applicable to grain-binders of the modern form known as the "Appleby" type, having the vertical revolving knotter-shaft with horizontal looper and a vertically-vibrating pivoted jaw that stands 40 over the breastplate at one side of the slot near the angle between the longitudinal and oblique reaches of the open slot of the breastplate, through which the binder-arm passes in placing the cord around the bundle and 45 over the tying-bill to the cord-holder and having a support or stop across said slot for the cord-strands at the inner side of the knotter-jaw as the tying-bill stands with its jaws pointing outwardly in the direction of 50 the oblique reach of the slot.

The invention relates first to the cord-holder, which is secured to the lower end of

a vertical shaft provided with a pinion that is intermittently actuated by the tier-cam, similar to that shown in English Patents No. 55 10,212, dated August 10, 1886, and No. 9,992, dated July 16, 1887, and well known in modern binders. My improvement therein consists in mounting, as hereinafter specified in the claims, the upturned annular cord-holding flanges upon separate curved arms secured to the hub that is keyed to the revolving shaft. The open space between these arms admits the escape of the loose fiber and pieces of the cord that are necessarily discharged from the cord-holder, thereby preventing it from being clogged up, the cord-cutting knives being also secured to two of these arms. The exteriors of the cord-holding flanges are provided with vertical corrugations, and at the front base are horizontal grooves to prevent the cord from slipping down and hold it up as it is brought against the outer pressure-shoe in the usual well-known manner. In my last-named former 70 patent I provide a depression at the inner side of the knotter on the upper surface of the breastplate, and in my present invention I provide a convex raised boss at the outer edge of the depression beneath the knotter-jaw, 75 which terminates in a rounded stop setting across the longitudinal reach of the cord-slot and holds the cord up to the knotter and prevents its escape therefrom until the knot is completed and being discharged with the outgoing bundle, the lower surface of the slot in the breastplate lengthwise of the base of the boss being cut away obliquely in a line trending to the outer or oblique reach of said slot and the boss having an upwardly-curved face 80 from said base-line to its crown, the construction admitting the free outward movement of the band as the bundle is being discharged to strip the knot from the knotter that has completed its revolution while the strands of 85 cord are detained by the stop. This convex raised boss is practically concentric with the axis of rotation of the knotter and is a little higher at the outer end to form the above-mentioned rounded stop and insure the detention of the cord until the knife has severed the ends of the band and the vibrating 90 jaw of the knotter has seized upon the same before it has slipped down toward the point 100.

of the knotter. This insures a perfect knot upon large bundles, where great strain upon the cord requires additional means to prevent the escape of the cord from the knotter-jaw.

- 5 In the drawings, Figure 1 is a plan view showing the knotter and cord-holder at the moment when the band is around the bundle beneath the breastplate and the knotter has nearly completed its revolution, the knotter-jaw being open and in the act of seizing the ends of the cord as the knife approaches the same to sever the band, the earlier movements of the binder having placed the cord by means of the needle and partially revolved 10 the knotter and cord-holder to the point herein shown. Fig. 2 is also a plan view showing the same as the knife severs the cord and the knotter-jaw has closed upon the ends of the strand in the completion of the knot prior to 15 its discharge in the continued movement of the parts in the usual well-known manner. Fig. 3 is a plan view in detail of the breastplate beneath the knotter, showing the depression and convex raised boss upon the 20 breastplate at the outer edge of the depression. Fig. 4 is a vertical section of the same on lines 4 4 of Fig. 3, also showing the lower surface a^5 and the curved end wall of the cord-slot on the right of Fig. 4 of said breast- 25 plate. Fig. 5 is a vertical section of the cord-holding disk. Fig. 6 is a plan view of the bottom of the breastplate turned over, showing more clearly the outward bottom surface 30 forming the oblique base-line of the boss shown in Fig. 4, which is an end view.

In the drawings, A represents the breastplate, B the knotter, and B' the cord-supporting finger shown in my former patents.

C is the hub or shaft of the cord-holder, to 40 which the flange-supporting arms C' are secured; C², the vertical cord-holding flanges, provided with corrugation c'; C³, the pressure-shoe; c, a horizontal cord-holding groove at the front base of the flanges C² to prevent 45 the escape of the cord as it is pressed in against the shoe.

c² is the knife; b, a cord-guide; a, the depression in the upper surface of the breastplate beneath the knotter; a', the convex 50 raised boss at the outer edge of the depression beneath the knotter-jaw, the same being slightly higher at its outer end a², which is extended across the stubble end of the longitudinal reach of the slot in the breastplate; 55 a³, the rounded stop, and a⁴ the oblique base-line of the boss.

In operation, the band being placed around the bundle and across the knotter-jaw in the usual well-known manner and the knotter revolved, as shown in Fig. 1, the cord is held to a position well up on the jaws and the ends extending to the holder are forced back into the jaws as the cord extending down around the bundle is prevented, by means of stop a³ 60 on the convex raised boss a' beneath the knotter, from escaping outwardly until the knotter has completed its revolution, when

the outward discharge of the bundle in the usual well-known manner will strip the knot from the tying-bill. It is important that both 70 strands of the cord be kept well up on the tying-bill until its jaw closes down, and it has been found in the binding of unusually-large bundles that this convex raised boss, formed as described, and shown in the drawings, prevents the escape of the lower cord that extends around the outside of the bundle and against which the pressure of the straw is greatest and also holds up the cord well onto the knotter as it revolves immediately over 80 it in the formation of the knot.

Having thus described my invention, what I claim, and desire to secure by Letters Patent, is—

1. In a cord-holder the revolving hub C, 85 provided with the narrow flange-supporting arms C', and the corrugated cord-holding flanges C² the supporting-arms secured to the ends of the flanges operating substantially as shown and described.

2. The combination of the narrow flange-supporting arm C', the cord-holding flange C², the supporting-arm secured to the end of the flange, said flange being provided with a knife c², and the pressure-shoe C³ operating substantially as shown and described.

3. In combination with the knotter revolving over the breastplate, and stopping with its point trending outwardly in the direction of the bundle-discharge, the breastplate, provided with an angular slot and having the depression a located at the reentrant angle of the slot, and the convex raised boss a' a² at the outer edge of the depression operating substantially as shown and described.

4. In combination with the knotter revolving over the breastplate, and stopping with its point trending outwardly in the direction of the outgoing bundle, the breastplate provided with an angular slot and having the convex raised boss a' at the reentrant angle of the slot terminating in a knob a² to receive thereon the strands of cord that are around the bundle, and prevent their escape from the knotter as the latter continues to revolve 115 and grasps the outer ends of the cord that extend to the cord-holder, until said cord is severed by the knife, to insure the ends being drawn through the loop as the discharge of the bundle strips the knot therefrom substantially as shown and described.

5. In combination with the knotter revolving over the breastplate, and stopping with its point trending outwardly in the direction of the outgoing bundle, the breastplate provided 125 with an angular slot and having the convex raised boss at the reentrant angle between the longitudinal and oblique reaches of the cord-slot upon the upper side and extending across the outer end of said longitudinal reach 130 and beneath the knotter-shaft, to hold the cord up to the knotter and prevent its escape during the formation of the loop.

6. In combination with the knotter the

breastplate provided with an angular slot, the knotter revolving over the breastplate and stopping with its point trending outwardly in the direction of the outgoing bundle, the 5 raised convex boss therebeneath at the reëntrant angle of the cord-slot, provided with a rounded stop and having an inclined lower

surface adjacent to the oblique reach of the cord-slot.
